SUN DIAL

John Garret Thew, Westport, Conn.

Application August 8, 1957, Serial No. 47,273

Term of patent 14 years

(Cl. D42—7)

Fig. 1 is a perspective view of a sun dial, showing my new design;

Fig. 2 is a side elevational view, and

Fig. 3 is a front elevational view thereof.

I claim:

The ornamental design for a sun dial, as shown.
